(57) **CLAIM**

I claim the ornamental design for a tool accessory case, as shown and described.

DESCRIPTION

FIG. 1 is a perspective view of the bottom and front of a tool accessory case;

FIG. 2 is a front view of the tool accessory case of FIG. 1;
FIG. 3 is a right view of the tool accessory case of FIG. 1;
FIG. 4 is a rear view of the tool accessory case of FIG. 1;
FIG. 5 is a left view of the tool accessory case of FIG. 1;
FIG. 6 is a top view of the tool accessory case of FIG. 1; and,
FIG. 7 is a bottom view of the tool accessory case of FIG. 1.

The design is the external appearance of the tool accessory case as shown in the drawings.
